CLAIM

The ornamental design for a storage bucket, as shown and described.

DESCRIPTION

FIG. 1 is a top perspective view of a storage bucket showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top plan view thereof; and,

FIG. 6 is a bottom plan view thereof.

Broken lines in the drawings depict portions of the storage bucket that form no part of the claimed design.
